COATING MACHINE

Robert J. Hutt and George A. Hutt, Brooklyn, N. Y.

Original application March 24, 1933, Serial No. 662,492. Divided and this application September 26, 1933, Serial No. 690,998

4 Claims. (Cl. 91—18)

This invention relates to improved "coating mechanism" for applying paste lines to a paper web or the like, which is drawn or fed along or over a supporting frame and is particularly adaptable to packaging machines such as shown and described in an application filed by us March 24, 1933, Ser. No. 662,492 and of which this forms a divisional application.

An object of this coating mechanism is to provide means for applying marginal lines of paste to a preferably intermittently moving web of paper, in this case a base web, on which the individual contents of packages may be placed, prior to receiving a printed transparent web thereon, said webs being subsequently sealed over the contents and cut into desired size packages simultaneously with the operation of mechanism for feeding said webs the distance of a dimension of one of said packages which operation is repeated over and over again to eject a complete package from the packaging machine at the end of each feeding movement of said webs and contents.

Another object of the invention is to provide means for applying transverse or cross lines of adhesive to said paper web at each dwell in the intermittent feeding movement, said cross lines preferably extending from one marginal paste line to the other to form appropriate bare spaces suitable for depositing the contents of packages to be completed by co-operating mechanisms forming no part of the present invention later set forth in a general description.

In the drawings:

Fig. 1 is a side elevation, with parts omitted, of a packaging machine of the type shown and described in the co-pending application above identified.

Fig. 1a is a diagrammatic perspective of part of a paper web showing lines of adhesive as applied by our invention.

Fig. 2 is a partial vertical longitudinal section of the paste applying mechanism of the invention and detached from the packaging machine, the line of section being about on the line 2—2 of Fig. 3.

Fig. 3 is a plan view of the said paste applying mechanism shown in Fig. 2 and partly in section;

Fig. 4 is a partial cross section on the line 4—4 of Fig. 3; and

Fig. 5 is a detail of one of a pair of racks employed.

Referring to the drawings in detail, the packaging machine, with which our invention may

co-operate may include a suitable supporting frame 10, comprising top side bars 11, corner legs or posts 12, and lower side bars 13, together with cross bars, rods or shafts if required to brace the frame laterally but in practice, the many operative cross shafts of the mechanism may act to tie the side frames or bars together.

At the rear end of the machine is a paste box 14, preferably mounted for forward and backward adjustment on supports 15 at each side of the machine (but one being shown) and on the opposite bottom corners of the paste box 14, are appropriate lugs or projections 16, which rest each in a pocket 17 formed in opposite rack bars 18, which are slidable on the supports 15, and are operated by a cross-shaft 19, having gear parts 20 to mesh with the rack bars 18, and said shaft is manually turned through a hand-wheel 21, fast thereto, for the purpose of adjustably sliding the paste-box 14, forwardly or backwardly on the frame 15, to change the tension or length of the horizontal pasted portion 22, of a comparatively heavy web or back-sheet 23, taken from a convenient source of supply 24, and drawn around an idle roller 25 upwardly and over a platen-roller 26, then forwardly to printing, sealing and feeding devices hereafter described.

Marginal, and spaced cross lines of paste 27 and 28, respectively, are applied to the web 22 between intermittent feeding movements of the platen roll 26, in the following manner and by devices which will now be described:

A feed-roller 29, dips into the paste 30 in paste-box 14 and is mounted on a cross-shaft 31, having fixed on an extended end thereof, a pair of gears 32, and loosely mounted to rotate freely on this extended end is a third gear 33, carrying a spring-pressed dog 34, in contact with the teeth of the outer of said fixed gears.

Constantly in mesh with the free running gear 33, is a reciprocating rack 35, operated by parts of the packaging machine.

The platen-roller 26, is driven through its shaft 36 and a gear 37 thereon, by a central gear 38 of a train including the inner one of the double gears 32; thus the longitudinal paste lines 27, are applied to the upper face of the web 23, by disk paste applying rollers 39 which are supported on a shaft 40, carrying the said central gear 38, said disk rollers having constant operative contact with the paste feed roll 29 and the said back-sheet 23, as it is drawn over the platen-roller 26.

In operation, the rack 35 when moving backward or to the right, rotates the loose-gear 33 and drags the dog or pawl 34 inoperatively over teeth of the outer one of the double gears 32, but 5 when the said rack starts forwardly the dog 34 picks up the double-gears 32, and through the said gear train, including the inner of the double-gears 32, central gear 38, and platen-roller gear 37, the rollers 29, 39 and 26 are turned to 10 permit a determined length of the web 23 to be drawn around and over the platen-roll 26, the length of the shift being the longitudinal dimension of a determined package to be formed by the machine.

15 Attached to suitable brackets 41, secured to the back of the paste-box 14 is a scraper-blade 42, extending longitudinally of the feed-roll 29 and in constant contact therewith, for arresting excessive paste carried upwardly on said roll 20 which paste excess flows back into said pan 14.

20 A rock-shaft 43, is journalled in bearings 44, extending upwardly from the rear corners of the paste-box 14, front bearings 45 on this box serving as journals for the platen-roller 26, as will 25 be obvious.

25 The rock-shaft 43, has a gear 46 keyed thereto, with which a gear-rack 47, secured to a cross-head 48, is meshed, and these parts are operatively held in mesh by a suitable two-part box 30 casting 49, having opposite tubular bosses 50 loosely encompassing the said rock-shaft for permitting the gear-rack 47 and the attached cross-head 48 to have oscillating movements for the purpose presently set forth; the two-part box casting being held together by a cross-bolt 35 or screw 51, see Fig. 2.

35 Fixedly supported above the ends of the paste-box, 14, are angle plates 52, each having an arcuate slot 53, through which pins 54 extending 40 from the ends of the cross-head 48 operate to guide and limit the movements of the said cross-head, when it is manipulated in the operation of the rock-shaft 43 through said gear-rack 47.

40 The rock-shaft 43 (Fig. 3) is extended at one side as at 55, and keyed to the shaft extension just outward of the corresponding bearing 44, is a friction gear or disk 56 provided with a frictional facing 57 adapted for coaction with a second friction gear or disk 58, united by a hub 59 45 with a spur gear 60 resting on and in constant mesh with the main power gear rack 35.

45 The unit constituted by the said second friction gear 58, the spur gear 60 and the connecting hub 59, is free on the shaft extension 55, and to 55 maintain the said friction gears and facing in proper operative contact for driving shaft 43, a charged spiral spring 61 is interposed between the spur gear 60 and a collar 62, pinned to said shaft extension 55.

55 The transverse paste lines 28, are applied to the back-web 23 in the following manner: A paste pad 63, (Fig. 2), is carried by the cross-head 48, and in the back stroke of the gear rack 35, when the web is at rest, the gears 60, 58, 56 and 46 on shaft 43, and the gear 65 rack 47, cooperate to move the cross-head forward to cause the projecting pins 54 to abut the forward ends of the arcuate slots 53, in the angle-plates 52, and assume the positions indicated in dotted lines in said Fig. 2, with the paste-pad 63, resting on said web over the platen-roller 26, to apply a transverse line of paste thereon, and when the power-rack 35 is 70 reversed, the motion of the above described co-operating gears and gear-rack will be reversed 75

for drawing the cross-head 48 backwardly, causing the pins 54 to abut the rear ends of said arcuate slots 53 and support the cross-head and paste pad slightly above and over the axis of the feed roller 29 with the paste pad clear 5 of said feed roller.

10 The arcuate slots have upturned rear ends as at 64, to suspend the head in a manner to cause the pad 63 to be maintained clear of the feed roller 29; but at the beginning of its forward movement, to apply a transverse paste line on the web, said cross-head takes a sharp drop to permit contact of the paste pad 63 with the feed roller 29, to pick up a fresh supply of paste therefrom.

15 The supporting frame 15 of the paste box and its associated parts, may be of any desired construction to permit of horizontal adjustment, through the operation of the gear or gears 20 and gear rack or racks 18.

20 The reciprocable gear rack may be operated by a motor 65, through an electric circuit 66 (Fig. 1) controlled by a switch 67. The motor has a shaft 68, having a worm and gear driving connection 69 with a master gear 70, mounted 25 to rotate with a cross shaft 200 on the ends of which are cranks 73 connected by crank-rods 74 to opposite rock arms 75 carried on a feeding and sealing carriage on which a cutter 186 is carried, as shown and described in 30 the copending application for packaging machines above referred to.

25 The cross lines 28, are applied to the web 22, by the pad 63, at near the time the cranks 73 are at or near their outward dead centers causing a dwell at the outward travel limit of the gear rack and just prior to the pick-up action of the pawl or dog 34, on the gear 33, for operating the gear train 32, 38, 37 to rotate the paste transferring rollers 29 and 39 and to impart a 40 web feeding rotary movement to said platen roll 26, thus this roll 26 performs a double function, i. e. as a platen for taking the thrust of the pasting pad when applying a cross line of paste to the web, and for feeding the web forwardly from the supply roll 24 under slight tension produced by a suitable spring 24a fastened at one end on the supporting frame; its free end having frictional contact with the web supply roll 24, as shown in Fig. 1 of the draw- 50

ings.

What we claim is:

1. In a coating machine, the combination with a supporting frame and a power member, of a paste box; gear means for adjusting its position; rotary means for feeding a web; rotary means for applying marginal paste lines to said web; angle plates mounted above said paste box and having each an arcuate slot; a reciprocatory cross-head having pins at its ends which project into said slots for guiding and limiting the operative movements of said cross-head; a paste applying pad carried by the cross-head and means and connections operated by said power member for operating said rotary feeding means, the rotary, paste applying means and the cross-head, and said pad for applying transverse paste lines to said web.

2. In a coating machine, the combination with a frame and a reciprocable powered toothed rack; of a paste box; an intermittently driven platen roller journalled at its forward end; a reversible shaft mounted over the rear of said paste box; a gear fixed on said reversible shaft; a housing around said gear; a rack bar opera- 70 75

tively connected with said gear and extending horizontally through said casing; coating friction disks, one loose, one fixed on said shaft; a spring for forcing the disks into driving contact; a gear on the loose disk and engaging the powered toothed rack; and means on the said rack bar for applying a paste line to a web resting on said platen when at rest and when said powered tooth rack is operated to the right, or rearwardly.

10 3. In a coating machine, a paste box; standard bearings at the corners thereof; angle plates fixed to said bearings and having arcuate guide slots; a coating pad supported by said slots; means for operating the coating pad in the arc of said slots; rack bars under said paste box; and a gear rod engaging said rack bars through

which the paste box may be adjusted in position.

4. In a coating machine, the combination of a frame; an intermittently powered slideable toothed bar; a paste box; gear means for adjusting its position longitudinally; arcuate guides on said paste box; a rotary platen for feeding a web; rollers for applying continuous marginal paste lines to said web; a cross head; a pad on the under face thereof; pins projecting from the ends of the cross head into engagement with 10 said guides; and gears and connections between said slideable toothed power bar and said cross head for moving the pad to the web in a fixed path between the dwells of the powered tooth bar feeding operations.
